Claims priority, application France Feb. 6, 1961

8 Claims. (Cl. 317—171)

Relays are already known which include a magnetic circuit with a permanent magnet producing a flux across the pole-pieces and the armature which may be increased or which may be reduced to zero by a flux produced by a winding inducing a magnetomotive force in said magnetic circuit.

Such relays are not sensitive since the flux produced by the winding should close over the permanent magnet, the reluctance of which is high and, consequently, any modification in flux in such a circuit requires a high number of ampere-turns; in order to increase the sensitivity of such relays, it has been proposed to provide them with a magnetic shunt constituted by a member of magnetic metal inserted between the two pole-pieces. It has also been proposed to resort to a magnetic shunt provided with a gap. In both cases, the total flux of the permanent magnet is subdivided between the elementary circuit closed over a fraction of the pole-pieces and the shunt and that including the pole-pieces and the armature. This subdivision of the fluxes is performed in relationship with the reluctances in the two circuits and it is necessary, in order to obtain a sufficient flux in the circuit passing through the armature, to provide a comparatively high shunt reluctance. It is therefore necessary to resort to saturated iron shunts, but, by reason of this saturation, the magnetomotive force required for the passage through said shunt of the flux produced in the armature, remains high. It has been attempted to bring a remedy to these conditions by resorting to a shunt provided with a gap. The relays obtained are much more sensitive than those provided with an iron shunt, but it has been found that it was still possible to increase their sensitivity.

As a matter of fact, it is possible to obtain the same flux in the circuit of the armature with an iron shunt having a lower reluctance, provided the flux passing through the shunt is very high, since the fluxes are subdivided between the two circuits in a ratio reverse of that of the reluctances. With the shunt relays of the types known hitherto, wherein the magnetic shunt circuit is closed over the pole-pieces, it is impossible to increase said total flux, since the pole-pieces of a highly magnetic metal are speedily saturated.

Our invention removes this drawback by closing the circuit of the permanent magnet over the actual shunt and by securing the pole-pieces formed by small uprights to two points of said shunt, so as to provide the magnetomotive force required for the armature circuit.

Consequently, our improved relay includes chiefly a permanent magnet, a magnetic circuit or shunt constituted by a member of a large cross-section extending from one pole of the magnet to the other, two pole-pieces of a highly magnetic metal secured to two points of said magnetic circuit or shunt, a winding carried by at least one of said pole-pieces and an armature cooperating with said pole-pieces.

It has already been proposed to adjust the sensitivity of such relays provided with a magnetic shunt by making the permanent magnet turn around the axis of symmetry of the pole-pieces, so as to make the flux induced in the magnetic circuits of the relay vary. Said adjust-

2

ment is efficient but the induced flux varies to a substantial extent only during the fraction of a revolution during which the surface of the pole-pieces separates from the surface of the magnet. Consequently, this requires a delicate adjustment. Furthermore, it is a known fact that the maximum magnetization of a permanent magnet is retained only if its magnetic circuit is permanently closed by a magnetic circuit of a low reluctance, which is not the case with this prior arrangement. By making the permanent magnet cooperate no longer with the pole-pieces but with the shunt in accordance with the invention, these drawbacks are overcome.

As a matter of fact and in accordance with a preferred embodiment of our invention, the magnetic circuit or shunt is constituted by a thick cylindrical dished member, of which the peripheral edge cooperates with the poles of the permanent magnet, the actual pole-pieces constituted by two small cylindrical uprights being carried by two diametrically opposed points of the dished member.

We obtain thus a shunt of a uniform cross section, whatever may be the location of the magnet revolving round its axis, while a low constant reluctance is obtained by reason of the excellent closure ensured by the peripheral annular edge of the shunt, the magnetomotive force at the lower ends of the small uprights being then an accurate sinusoidal function of the angle formed by the plane passing through the axes of the uprights with the axis of the magnet poles.

It is also possible to ensure a partial or complete adjustment through a second shunt positioned on the surface of the permanent magnet opposed to the first-mentioned shunt and said second shunt is either axially movable, so as to provide a modification in size of the gap separating it from the magnet, or else, it is revolvable so as to make the area of its surface facing the magnet poles vary. Said adjustment by means of a second shunt may be associated with the adjustment provided by the rotation of the magnet, the second shunt adjusting the value of the flux in the first shunt, while the rotation of the magnet adjusts the sinusoidally varying value of the component of the magnetomotive force generating the flux in the armature circuit.

Our invention will be better understood from the reading of the following disclosure given by way of example, reference being made to the accompanying drawings, wherein:

FIG. 1 is a diagrammatic cross-sectional view of the relay in its open condition.

FIG. 2 is a corresponding view with the relay in its closed condition.

FIG. 3 is a view corresponding to FIGS. 1 and 2, the relay being in the condition corresponding to the beginning of its release.

FIG. 4 is a diagrammatic end view of the relay taken from the left side of FIG. 1.

FIG. 5 is a diagram showing the variation of the flux in the shunt as a function of the magnetomotive force produced by the winding or windings.

FIG. 6 is an axial sectional view of a first embodiment of the relay when complete.

FIG. 7 is an exploded view of the relay illustrated in FIG. 6, showing the main components thereof.

FIG. 8 is a view corresponding to FIG. 6, of a second embodiment.

FIG. 9 is an exploded view of a modification of the section including the permanent magnet and the shunts of a third embodiment.

The relay according to our invention includes essentially a permanent magnet 1, a shunt 2 of mild magnetic steel, two small uprights 3 of a magnetic material hav-

ing a high permeability, forming the pole-pieces and secured to the magnetic shunt at two potentiometrically selected points thereof, windings 4 surrounding said uprights, an armature blade 5 of a magnetic material, having a high permeability and a spring 6 exerting on the armature a force opposing magnetic attraction.

In the case illustrated in FIG. 1, the magnet 1 produces a flux in the shunt 2. Considering on the shunt 2 two points N_1 and S_1 to which the small uprights 3 of a high grade magnetic material are secured, we will assume that for the above-described relay, the gaps formed by the armature in the relay when closed, have a width of two microns with a surface of 0.05 sq. cm. and that the induction required for obtaining the desired attractive force, adapted to hold the armature against the force exerted by the spring with a suitable margin of safety, is equal to 5,000 gauss. In such a case the flux in the circuit passing through the gaps of the armature will be $5000 \times 0.05 = 250$ maxwells. The magnetic permeability of the pole-pieces and of the armature being very high, it is possible to consider only the reluctance of the gaps in the circuit passing through the pole-pieces. This reluctance is $0.0004 \div 0.05 = 0.008$, which requires for the passage of a flux of 250 maxwells a magnetomotive force of 1.6 ampere-turns.

When the relay is closed, as shown in FIG. 2, the total flux of the permanent magnet is subdivided between the two circuits: the cross-section of the shunt and the magnetomotive force of the permanent magnet are selected in a manner such that the total flux ϕ_F may be equal to 2,250 maxwells, of which 2,000 maxwells forming the flux $\phi_F - \phi_r$ pass through the shunt between N_1 and S_1 , while the remaining 250 maxwells forming the flux ϕ_r pass through the armature circuit. The reluctance of the shunt between N_1 and S_1 should therefore be equal to:

$$\frac{1.6}{0.8 \times 2,000} = 0.001$$

In the following disclosure, we will assume that the magnetomotive force across the terminals of the shunt which is produced by the permanent magnet, is equal to 3 ampere-turns and this shows that the total reluctance of the shunt should be equal to 0.00178. When the armature circuit is open, the total flux ϕ_0 in the shunt becomes equal to:

$$\phi_0 = \frac{3}{0.8 \times 0.00178} = 2,106 \text{ maxwells}$$

and the magnetomotive force between N_1 and S_1 is equal to 1.685 ampere-turns.

In order to cut out completely the flux ϕ_r , it is necessary therefore to produce in the circuit of the armature an antagonistic magnetomotive force of 1.685 ampere-turns in the opposite direction. As a matter of fact, the armature circuit opens when the flux passing through the shunt between N_1 and S_1 has a value ranging between the two values ϕ_0 and $\phi_F - \phi_r$, that is, equal to ϕ_S with a magnetomotive force between N_1 and S_1 rising between 1.6 and 1.685 ampere-turns. The magnetomotive force between N_1 and S_1 rising from 1.6 to 1.685 ampere-turns, while the magnetomotive force produced by the winding 4 rises from 0 to 1.685 ampere-turns, the release is obtained for a number of ampere-turns in the winding 4 lying between 0 and 1.685 ampere-turns.

As a matter of fact, the reluctance of the shunt varies; the value 1.685 ampere-turns is only an approximate value and it is therefore interesting to select a shunt having a maximum permeability and to obtain a ratio $\phi_0/\phi_F - \phi_r$ as near unity as possible (FIG. 5).

When it is desired to adjust the relay, it is possible to make the magnetomotive force between the points N_1 and S_1 vary. In these previously known relays, in which the magnet was adapted to rotate, the modification in the magnetomotive force was obtained by a modification in the flux sent into the magnetic circuit, which modification

was produced by a reduction of the cross-section of the gap at the junction between the magnet and the magnetic flux. In practice, such a modification is very speedy with reference to the rotation of the magnet and it is obtained suddenly, which makes the adjustment a difficult matter. With our improved relay (FIG. 4) wherein the shunt 2 is given a shape of a cylindrical cup or dished member having a broad peripheral track 7 engaged by the poles of the circular magnet 1, provided advantageously with two flat parallel lateral surfaces 8, the total flux inside the shunt will be constant and equal to a maximum by reason of the low reluctance of the contact gaps of a large area and very reduced width. The magnetomotive force between two points of a magnetic flux being proportional to the spacing of said points measured along a line parallel with the axis of the flux, it is apparent that the electromotive force between N_1 and S_1 varies in the same manner as the cosine of the angle α , which is the angle of the magnetic axis of the magnet 1 with the line N_1S_1 . The total flux in the shunt being defined by the permanent magnet 1 and the characteristic properties of the shunt formed by the cup 2, the modification in the magnetomotive force in the armature circuit is an arcuate sinusoidal function of said angle α . If the total flux of the shunt is caused to vary in any known manner, for instance by means of a secondary shunt which deflects a fraction of the flux of the permanent magnet, the value of the magnetomotive force will be a function of said further flux, but the rotation of the flux thus modified by the rotation of the magnet and of the secondary shunt will still provide a sinusoidal modification of the magnetomotive force.

FIGS. 6 and 7 illustrate a mechanical embodiment of the above-described relay. Said relay includes a cylindrical permanent magnet 1 with two parallel flat sides 8 along its lateral surface. As disclosed hereinafter, said magnet can revolve round a spindle of an amagnetic metal passing through an axial bore 9 in said magnet. The magnet 1 cooperates with a circular dished shunt 2 made of mild magnetic steel and of which the edge 7 forms an annulus bearing against the ends of the permanent magnet 1. Said dished shunt 2 is also provided with an axial bore 10. Its thickness is such that under the action of the flux generated by the permanent magnet, said shunt shows a maximum permeability and the magnetic flux passing through it is far from saturation flux.

The bottom of the dished shunt 2 is provided at two diametrically opposed points with bores inside which are fitted with a force fit the lower ends of two small cylindrical uprights 3 made of a highly magnetic material, that is, a material which provides a maximum permeability; in order to obtain however a sufficient induction in the gaps between the armature and the pole-pieces, the ends 11 of the uprights or pole-pieces 3 have a smaller diameter and, in order to reduce to the utmost the reluctance of the gap in front of the pole-pieces, the terminal surfaces of said pole-pieces are polished with a very high accuracy, so as to ensure a gap of only a few microns with the armature blade.

Two windings 4 are fitted over the small uprights 3 and are connected in series. They are held in position by a clamping plate 12 made of plastic material and fitted over the ends of the pole-pieces, while leaving the ends 11 of the latter free. The plate 12 clamping the windings carries two studs 13 which serve for the guiding of the armature and its outer surface is provided round the central bore 14 in the plate with an arcuate recess in which is housed the lower end of frusto-conical spiral spring 15 corresponding to the spring 6 of FIGS. 1 to 3.

The armature rod 16 passes coaxially through the bores 9, 10, 14 in the permanent magnet 1, the dished shunt 2 and the clamping plate 12. It carries at its end facing the ends of the pole-pieces the armature 5 made of high grade magnetic material. Its ends are provided with grooves engaged by circlip washers 17.

The relay illustrated in FIG. 8 is, for its major part, identical with that described hereinabove and the same components are designated by the same reference numbers. However, the bore 10, in the dished shunt 2, is tapped so as to be engaged by the threaded end of a rod 18 inside the hollow shunt of which the armature rod 16 can slide freely. The bore 9 in the magnet 1 has an enlarged diameter so as to allow the passage through it of the threaded rod 18. A secondary dished shunt 19 made of mild steel, of a shape similar to that of the shunt 2, is fitted over the bolt 18 and its peripheral upstanding flange faces the magnet 1. It is held spaced from the magnet 1 by a spring 20 and it can be urged nearer said magnet by screwing down the threaded rod 18. The adjustment of the gap between the magnet 1 and the secondary shunt 19 provides a modification in the absolute value of the flux produced in the primary shunt 2. The rotation of the permanent magnet 1 provides a sinusoidal modification of the magnetomotive force generated between the two uprights or pole-pieces by the flux of which the value is in its turn adjusted by the shunt 19.

FIG. 9 illustrates a modification of the adjusting section which provides the adjustment solely through rotation of a secondary shunt 21. To this end, the magnet is held fast in position by projections 22 forming abutments on the primary shunt 2 for the lateral flat surfaces 8 of the magnet. The secondary shunt 21 is formed by a cylindrical dished member provided with two flat lateral surfaces 23, so as to allow a modification in the area of the gap between the shunt 21 and the magnet 1. The secondary shunt 21 is urged towards the magnet 1 by an elastic washer 24 clamped in position by the threaded rod 18.

The above-described embodiments, given by way of examples, may be modified in any desired manner within the scope of the accompanying claims.

What we claim is:

1. A highly sensitive relay, comprising a permanent magnet, a magnetic dished shunt including a bottom, the thickness of which is the same as that of the magnet, a thick upstanding peripheral annular wall concentrically arranged with reference to the magnet and on which the ends of the magnet rest, two elongated pole-pieces of a highly magnetic material rigidly secured to two diametrically opposed points of the bottom of the shunt and facing away from the magnet, a winding carried by at least one of said pole-pieces, an armature facing the outer ends of the pole-pieces, and elastic means urging the armature away from the pole-pieces.

2. A highly sensitive relay, comprising a permanent magnet, a magnetic shunt including a central part and upstanding terminal parts on which the ends of the magnet rest, two elongated pole pieces of a highly magnetic material rigidly secured to two longitudinally spaced points of the central part of the shunt and facing away from the magnet, a winding carried by at least one of said pole-pieces, an armature facing the outer ends of the pole-pieces, and elastic means urging the armature away from the pole-pieces.

3. A highly sensitive relay, comprising a permanent magnet, a magnetic shunt including a central part the thickness of which is substantially the same as that of the magnet and upstanding terminal parts on which the ends of the magnet rest, two elongated pole-pieces of a highly magnetic material rigidly secured to two longitudinally spaced points of the central part of the shunt and facing away from the magnet, a winding carried by at least one of said pole-pieces, an armature facing the outer ends of the pole-pieces, and elastic means urging the armature away from the pole-pieces.

4. A highly sensitive relay comprising a permanent magnet, a magnetic dished shunt including a bottom and an upstanding peripheral annular wall concentric with the magnet and on which the ends of the magnet rest, two elongated pole-pieces of a highly magnetic material rigidly secured to two diametrically opposed points of

5 the bottom of the shunt and facing away from the magnet, a winding carried by at least one of said pole-pieces, an armature facing the outer ends of the pole-pieces, and elastic means urging the armature away from the pole-pieces.

5. A highly sensitive relay comprising a permanent magnet, a magnetic dished shunt including a bottom, thickness of which is substantially the same as that of the magnet, and a thick upstanding peripheral annular wall concentric with the magnet and the periphery of which registers with the magnet poles to allow the latter to slide along said periphery, a spindle of a non-magnetic material axially connecting said permanent magnet and said shunt so as to allow relative angular movement between the permanent magnet and the shunt, two elongated pole-pieces of a highly magnetic material rigidly secured to two diametrically opposed points on the bottom of the shunt and facing away from the magnet, a winding carried by at least one of said pole-pieces, an armature facing the outer ends of the pole-pieces, and elastic means urging the armature away from the pole-pieces.

6. A highly sensitive relay comprising a permanent magnet, a first magnetic dished shunt including a bottom and an upstanding peripheral annular wall concentric with the magnet, the periphery of said first shunt registering with the magnet poles to allow the latter to slide along said periphery, a second magnetic shunt shaped as a dished cylindrical element with two flat lateral surfaces, the parts of the upstanding annular wall of which are concentrically arranged with reference to the magnet and rest on the surface of the permanent magnet facing away from said first shunt, a spindle of a non-magnetic material axially connecting said permanent magnet and both said dished shunts while allowing the angular shifting of said second shunt relative to the permanent magnet and of the permanent magnet relative to said first shunt, two elongated pole-pieces of a highly magnetic material secured to two diametrically opposed points on the bottom of said first shunt and facing away from the magnet, a winding carried by at least one of said pole-pieces, an armature facing the outer ends of the pole-pieces, and elastic means urging the armature away from the pole-pieces.

7. A highly sensitive relay comprising a permanent magnet, a first magnetic dished shunt including a bottom and an upstanding peripheral annular wall concentric with the magnet on which the ends of the magnet rest, a second magnetic shunt shaped as a dished cylindrical element with an upstanding annular wall concentrically arranged with reference to the magnet and facing the surface of the permanent magnet facing away from said first shunt, a spindle of a non-magnetic material axially connecting said permanent magnet and both said dished shunts, means cooperating with said spindle and said second shunt to displace said second shunt towards and away from the permanent magnet, two elongated pole-pieces of a highly magnetic material secured to two diametrically opposed points on the bottom of said first shunt and facing away from the magnet, a winding carried by at least one of said pole-pieces, an armature facing the outer ends of the pole-pieces, and elastic means urging the armature away from the pole-pieces.

8. A highly sensitive relay comprising a permanent magnet, a first magnetic dished shunt including a bottom and an upstanding peripheral annular wall concentric with the magnet, abutments provided in said annular wall between which the ends of the magnet rest, a second magnetic shunt shaped as a dished cylindrical element with two flat lateral surfaces, the parts of the upstanding annular wall of which are concentrically arranged with reference to the magnet and rest on the surface of the permanent magnet facing away from said first shunt, a spindle of a non-magnetic material axially connecting said permanent magnet and both said dished shunts while allowing the angular shifting of said second shunt relative to the permanent magnet, two elongated pole-pieces

of a highly magnetic material secured to two diametrical-
ly opposed points on the bottom of said first shunt and
facing away from the magnet, a winding carried by at
least one of said pole-pieces, an armature facing the outer
ends of the pole-pieces, and elastic means urging the 5
armature away from the pole-pieces.
